ROOF CONSTRUCTION

John F. Blaski, Chicago, Ill.

Application July 11, 1945, Serial No. 604,424

6 Claims. (Cl. 108—1)

1

This invention relates to a construction for a roof or the like, and more particularly to a panel or section from which such construction may be fabricated.

In the building of a trussless roof for example, namely, that type characterized by an absence of trusses and supports distributed over the building area, and in which the roof is so contoured as to enable it to be supported directly on the foundation, it is highly important that great rigidity be inherent therein. The absence of trusses, cross-braces and columns gives rise to problems which must be solved in the design of the panels or sections comprising the roof, and embracing the factors of lateral and longitudinal thrust and direct loading.

While roofs of this general type have been heretofore known, many of them suffer from the shortcoming that insufficient attention has been devoted to increases in strength made possible by appropriate construction of the panels proper as contrasted with their mode of assembly. Thus, roof panel sections have been proposed wherein the major or flat extent of the panel has been corrugated in conventional manner and the panels are provided with simple flanges whereby adjoining sections may be mutually secured. However, the corrugations do not continue into the flanges to impart additional strength thereto, and the full benefit of proper flange construction has not been availed of. Moreover, panels for trussless roofs have been proposed in which no attempt has been made to conform the sections to the transverse curvature of the roof, for example, semi-elliptical, thus failing to utilize the greater load bearing ability of such curved sections.

My invention has for its principal object the provision of a metallic roof or ceiling panel preferably longer than it is wide and having a transverse cross section which is substantially trough-shaped, longitudinal marginal portions of the blank having been upturned to form the sides of the trough, and the free edges of the sides being so formed as to be engageable with interlocking portions of adjacent panels for rapid assembly and disassembly.

A further object is to provide a panel as just described in which one upturned side of the panel is bent outwardly upon itself to form an open fold or hem and the other or opposite upturned side is left unfolded. Thus adjacent sections may be overlappingly engaged by means of the two different edge formations aforesaid to effect a joint impervious to the entry of wind, moisture,

2

dust and other undesirable foreign elements. Moreover, it is a further aim to provide the interengaging edges as aforesaid with registering apertures through which bolts, rivets or like means may be passed for rapid erection or disassembly.

An additional object comprehends the provision of a panel as aforesaid in which the upturned sides are of substantial depth in comparison to the width of a section.

A further object resides in the provision of trough-shaped panels as aforesaid in which the bottom as well as a major portion of the sides are corrugated transversely in a novel manner, the transverse cross section of the corrugations consisting of a sine curve and the amplitude of the curve being a maximum at the center of the panel and gradually decreasing to zero where the corrugations are terminated just below the interengaging joints aforesaid.

Another object is to provide in panels as aforesaid apertures through the bottom thereof at the two ends and adapted to register with similar apertures in overlapped adjacent sections and means, for example, rivets or bolts adapted to pass through said apertures to maintain the sections in overlapped relation.

Still another object is to form a panel constructed as aforesaid with an arcuate contour in a direction corresponding to the curvature of the roof at a zone whereat the panel is to be installed.

In carrying out the invention in one form I provide panels substantially longer than they are wide and having a trough-shaped transverse cross section. The panels are preferably preliminarily curved by corrugating in the manner hereinafter described to correspond with the contour of a roof to be fabricated therefrom, for example, an arc of an ellipse. One upstanding side of the panel is formed initially slightly higher than the other and reversely folded to the exterior to form a narrow U-shaped flange or hem defining a channel just sufficient in width to receive therein the adjacent unfolded flange of an adjacent panel. Each of the panels is provided with apertures in its two upstanding sides, those apertures at the hem passing through both sides of the hem and whereby the interengaged panels may be joined in staggered relation by means of bolts or rivets. At each end the panel is provided with a plurality of apertures in order that endwise adjacent panels, when assembled, may be overlapped at their ends and bolts or rivets passed through said apertures for fastening the

same. For imparting additional rigidity to a panel and effecting the proper curvature thereof, it is corrugated in a novel manner, the major axis of each corrugation being disposed transversely of the panel and the corrugations jointly forming a sine curve in planes longitudinally of the section and normal to the surface thereof. The corrugations are characterized by being of maximum amplitude in the plane passing through the medial axis of the panel, and the amplitude of the curve being gradually decreased until there is reached a line just below the interengaging edges of adjacent sections.

In the drawings, which show a preferred form of the invention and certain alternative embodiments thereof:

Fig. 1 is a somewhat schematic cross section taken transversely of a roof fabricated from the panels of my invention;

Fig. 2 is a plan view of a portion of the roof of Fig. 1, also somewhat schematic;

Fig. 3 is a detailed plan view of a panel;

Fig. 4 is a detailed side elevational view of the panel of Fig. 3;

Fig. 5 is a cross sectional view taken on the line 5—5 of Fig. 2;

Fig. 6 is a partial detailed plan view of a portion of the roof of Fig. 2 and on larger scale;

Fig. 7 is a cross sectional view taken on the line 7—7 of Fig. 5;

Fig. 8 is a cross sectional view taken on the line 8—8 of Fig. 5;

Fig. 9 is a cross sectional view taken on the line 9—9 of Fig. 5;

Fig. 10 is a chart to indicate the form of the corrugations in their relation to the panel;

Fig. 11 is a cross sectional view, similar to Fig. 5, of an alternative form of panel; and

Fig. 12 is a cross sectional view, similar to Fig. 5, of another alternative form of panel.

Directing attention now to Figs. 1 and 2, I have shown a trussless roof 10 comprising the panels of my invention, the contour of the roof being indicated as semi-elliptical and supported on foundations 11. As clearly seen in Fig. 2, the panels 12 are preferably arranged in rows transversely of the roof and with the panels of a row staggered with respect to those in adjacent rows. A sufficient number of such rows is employed to comprise a complete roof.

In Figs. 3 and 4 there is shown a single panel 12 comprising a single thin sheet of metal, e. g., galvanized steel formed in a punch press or otherwise into a trough-shaped transverse cross section (Fig. 5), the bottom 13 of the panel being preferably flat and the sides 14 and 15 joining the bottom in segments of a substantially cylindrical surface of substantial radius. The side 14 is initially lower than the side 15 and the latter is then reversely folded in the press to the exterior of the panel to yield a narrow downwardly-disposed U-shaped flanged edge or open hem 16. The interior of the hem 16 is made of sufficient width to receive snugly therein the unfolded edge 14 of the adjacent panel or panels.

It will be understood that the thickness of the metal used for a panel will depend upon the strength desired to be imparted thereto. In general, this thickness will be such that the hem 16 may, at the time of erection, be opened wider with a screw driver or similar tool in order that two endwise overlapped panels may be received within the hem as will be pointed out herein-after. If the thickness of a panel will not permit ready deformation of the fold 16 in the field it is

within the scope of the invention to preform the end zones of the hem to receive such overlapped panels.

Adjacent the upper edge of the sides 14 and 15 the panel is provided with a plurality of equally spaced apertures 21 (Figs. 4 and 5), the apertures being so situated with respect to each other and the ends of the panel as to permit endwise overlapped panels in any selected row to be readily fastened to similarly overlapped panels in adjacent rows. Bolts 22 or rivets may be passed through the apertures 21 for maintaining the assembled panels in predetermined position and in rigid relationship. It will be understood that the panels may, if desired, be fabricated without the apertures 21 and that the same may be punched in the field before or after assembly by means of a suitable punch and die. Alternatively the joined sections may be welded.

From Fig. 4 it will be noted that each panel is preferably preformed into arcuate contour along its longer axis, the curve imparted to a panel corresponding to the curvature of that portion of the roof the panel is intended to occupy. Due to the rigid nature of a panel it is not ordinarily a simple matter to curve the same during erection although it is possible, by reason of the corrugations to be described, to curve a panel, to fit the contour of the roof without the specific initial forming aforesaid. That is to say, the forming of a roof panel having a generally U-shaped or trough-like transverse cross section to provide a particular arcuate contour along the longitudinal axis, as clearly indicated in Fig. 4, would, in the absence of the corrugations, result in an indiscriminate buckling of the sheet. The upstanding sides not only would tend to resist bending thereof in an edgewise direction, but to resist the arcuate forming of the substantially horizontal bottom portion. In a roof section of relatively heavy gauge, such buckling and distortion would yield a panel unfit for use or at least one which could be rendered fit only by considerable handwork.

By employing a trough-shaped blank and transversely corrugating the bottom and sides thereof so that the corrugations are of maximum amplitude in a plane normal to the bottom of the trough and centrally longitudinal thereof, and gradually diminish in amplitude toward their termination in the sides of the trough, the material of the blank is shortened by a maximum amount along its central longitudinal axis and by a gradually lesser amount along the two sides, thereby imparting the arcuate contour to the panel as seen in Fig. 4. By regulating the amplitude of the corrugations and the rate of diminution of the amplitude as aforesaid, any desired contour, within reasonable limits, may be provided. Otherwise stated, by changing the amplitude, any desired crimping of the metal may be achieved over specific longitudinal segments of the panel, while the resulting corrugations serve to stiffen the sheet.

At each of its ends the panel 12 is provided with a series of spaced-apart apertures 24 whereby, upon endwise overlapping of the panels in a row, bolts or rivets may be passed therethrough to fasten the panels together.

In Fig. 6 a portion of an assembled roof comprising panels 10a, 10b, 10c and 10d is shown. The preferred method of erection would consist in first assembling the endmost row of panels including 10a, beginning at ground level, then engaging panels such as 10b, 10c, etc., for the adjacent row, the panels being overlapped in the

down-roof direction both ways from the ridge or center line of the roof, the hem 16 of the row 10b, 10c, etc., being engaged over the unhemmed side 14 of the row 10a, etc. For greater rigidity the endwise overlapped joints, for example, 20, are, in adjacent rows, staggered with respect to each other. Bolts are employed to fasten the panels together as clearly shown in Fig. 6. After completion of the row 10b, 10c, etc., the succeeding row including 10d, etc., will be erected with its endwise joints staggered with respect to those in the preceding row. It is to be noted that the hem 16 of an up-roof panel overlies the hem 16 of the lower down-roof panel. Thus shedding of rain is properly effected not only as to these longitudinal joints but as to the transverse joints 20. It will be understood that alternate rows will include panels of half-length where necessary to enable erection in staggered relation as described.

A primary feature of the invention resides in the novel manner of corrugating the panels. The corrugations 25 (Figs. 3, 4 and 5) are continuous over the bottom 13 and the major portion of the sides 14 and 15 (Fig. 5) and are disposed transversely of the longer axis of a panel. The corrugations follow one another and are not distributed in spaced apart relation, any plane passing through a longitudinal element of the panel and perpendicular to the surface of the panel intersecting all said corrugations to form a sine curve corresponding to the formula:

$$y = r \sin x$$

where

y is the ordinate measured from the axis of x for any point of the curve

r is the amplitude and

x is the abscissa of the point.

At the longitudinal axis of the panel r is a maximum, and the corrugations terminate just below the zone of overlap of a hem 16 with a side 14, at which line the parameter r is zero.

In Figs. 7, 8 and 9 are shown three typical cross sections transversely of a group of corrugations 25, from which figures taken in conjunction with Fig. 5 it will be noted that over substantially the entire flat portion of the bottom 13 the corrugations are of maximum amplitude, and that the amplitude decreases as the line of termination of the corrugations is approached on either side. The chart of Fig. 10 illustrates this reduction of the amplitude from a maximum value of $r(r=1)$ to zero.

The selection of a sine curve for the cross sectional contour of the corrugations allows the reduction of the depth thereof from maximum to zero with a linear decrease of stress absorption. That is to say, as the stresses on the panel decrease from the central axis to the sides the corrugations decrease in depth linearly proportionately. Thus no abrupt change from the deeper portions of a corrugation to the shallower portions thereof is encountered as would be the case using corrugations whose cross sectional contour consists of the conventional arcs of a circle joined end to end or of any curve other than the sine curve. Any such abrupt changes set up localized lines of weakness with consequent danger of rupture under stress. My invention eliminates this disadvantage by providing an uninterrupted transfer of stress from one longitudinal narrow zone of a panel to the next narrow zone and thus progressively from the center toward the sides where the vertically disposed portions of the panel

offer a greater moment of inertia to absorb bending stress and the corrugations need not be of full depth. Moreover, by terminating the corrugations below the overlapping joints of adjacent panels the hem 16 and its mating edge 14 may be closely interlocked to effect a tight, weatherproof joint.

In Figs. 11 and 12 are shown cross sectional views corresponding to that of Fig. 5 but of alternate embodiments of my invention. For certain types of roofs it may be found advisable to modify the transverse general cross section of a panel from the shallow U-shape of Fig. 5 to the substantially V-shape of Fig. 11 or the trapezoidal shape of Fig. 12. However, the description heretofore given as to the disposition and function of the corrugations and their relation to the panel applies with the same force in connection with the forms of Figs. 11 and 12.

20. While I have shown particular embodiments of my invention, it will be understood, of course, that I do not wish to be limited thereto since many modifications may be made, and I, therefore, contemplate by the appended claims to cover any such modifications as fall within the true spirit and scope of my invention.

Having thus described my invention, what I claim and desire to secure by Letters Patent is:

1. A structural panel adapted for use in multiple in a roof or the like comprising a relatively thin blank marginally bent to form a trough-shaped member having a substantially segmental cylindrical longitudinal configuration, the bottom of the member and the major extent of the sides thereof being provided with a plurality of corrugations disposed transversely of the member, the depth of the corrugations being a maximum over substantially the entire width of said bottom and gradually decreasing on both sides toward zero at the free edges of said sides, whereby said graduated corrugations provide the said segmental cylindrical configuration without buckling of the member, one longitudinal edge of the panel being provided with an outwardly turned-over lip adapted to overlie the adjacent upturned lip of a neighboring panel.

2. A structural panel adapted for use in multiple in a roof or the like comprising a relatively thin blank bent to form a trough-shaped member, corrugations transversely of the axis of the member, the amplitude of the corrugations being a maximum in a plane longitudinally centrally of the member and the amplitude decreasing gradually from both sides of said maximum toward the free edges of the sides of the member, the depth of the corrugations in the said plane reducing the length of the member to the greatest extent in said plane and to a gradually lesser extent towards the said free edges to provide a panel of predetermined substantially segmental cylindrical longitudinal configuration free from buckling, one longitudinal edge of the panel being provided with an outwardly turned-over lip adapted to overlie the adjacent unturned lip of a neighboring panel.

3. A structural panel adapted for use in multiple in a roof or the like comprising a relatively thin flat blank bent to form a trough-like member, corrugations transversely of the axis of the member, the amplitude of the corrugations being a maximum in a plane normal to and disposed centrally longitudinally of the member and the amplitude decreasing gradually on both sides of said plane toward the free lateral edges of the member, whereby uniform curvature longitudi-

dinarily of the member is provided without buckling, one longitudinal edge of the panel being provided with an outwardly turned-over lip adapted to overlie the adjacent unturned lip of a neighboring panel.

4. The method of forming a structural panel from a flat blank which method comprises bending two opposed marginal lateral portions of the blank to provide a trough-like member, and transversely corrugating the member to impart an arcuate longitudinal configuration to the member, the corrugations being impressed to a maximum in a zone substantially centrally longitudinally of the member and shallower at the ends of the corrugations, the corrugations terminating in the sides of the members.

5. The method of forming a structural panel from a flat blank, which method comprises bending the blank to provide a trough-like member, and transversely corrugating the member to impart an arcuate longitudinal configuration to the member, the corrugations being impressed to a maximum in a plane normal to the member and passing through the longitudinal central axis thereof and shallower at the ends of the corrugations, the corrugations terminating adjacent the free lateral edges of the member.

6. A structural panel adapted for use in multiple in a roof or the like comprising a relatively thin, flat, elongated blank bent transversely to form a trough-like member, said member having corrugations disposed transversely of the longitudinal axis of the member, the amplitude of the

corrugations being maximum in a plane normal to and disposed centrally longitudinally of the member and the amplitude decreasing gradually on both sides of said plane toward the longitudinal edges of the upturned sides of the member, whereby the panel is provided with a curvature longitudinally of the member, one edge of the member having a plurality of apertures spaced apart along the length of the member, the opposite edge having a downturned lip adapted to engage the unturned lip of an adjacent panel and both the lip and side of the member adjacent thereto having a plurality of apertures therethrough and spaced along the extent thereof in register with the apertures of the unturned edge of the adjacent panel.
